Primary Examiner — Sheryl Lane*Assistant Examiner* — Aula Soroush(74) *Attorney, Agent, or Firm* — Jeenam Park(57) **CLAIM**

The ornamental design for a cage, as shown and described.

DESCRIPTION

FIG. 1 is a perspective view of a cage, showing our new design;

FIG. 2 is another perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a rear view thereof;

FIG. 8 is a front view thereof;

FIG. 9 is an enlarged view of portion of FIG. 1;

FIG. 10 is an enlarged view of portion of FIG. 1; and,

FIG. 11 is an enlarged view of portion of FIG. 1.

The broken line showing of the cage is for the purpose of illustrating article and forms no part of the claimed design. The dot-dash line enclosing the enlarged portions are for depicting the boundary of the enlarged view and form no part of the claimed design.
